[57] CLAIM

The ornamental design for a fence, substantially as shown and described.

DESCRIPTION

FIG. 1 is a perspective view of a fence constructed in accordance with the invention;

FIG. 2 is an expanded, partially broken away view of portions of the fence illustrated in FIG. 1;

FIG. 3 is an elevation view of a cap for the fence illustrated in FIG. 1;

FIG. 4 is a section view of a portion of the fence illustrated in FIG. 1, taken substantially on the line 4—4 in FIG. 1.
